UNITED STATES PATENT OFFICE

WILHELM B. BRONANDER, OF MONTCLAIR, NEW JERSEY

FIRE EXTINGUISHER AND SUPPORT THEREFOR

Application filed January 24, 1928, Serial No. 248,999.

This invention relates to fire extinguishers and supports therefor.

The invention relates more particularly to the type of extinguisher having a fire extinguishing liquid sealed therein such, for instance, as carbon tetrachloride.

The invention has for its salient object to provide an extinguisher and support therefor so constructed and arranged that the extinguisher is easily accessible and can be readily and quickly utilized to extinguish a fire.

Another object of the invention is to provide a frangible extinguisher and support so constructed and arranged that the extinguisher will be protected from accidental breakage but can be easily and quickly broken to release the fire extinguishing fluid therein in case of fire.

Another object of the invention is to provide an extinguisher casing so constructed and arranged that the container having therein the extinguishing liquid can be easily and readily replaced after the device has been used to extinguish a fire.

Another object of the invention is to provide an extinguisher support that is simple, practical and inexpensive in construction and so constructed and arranged that the extinguisher can be easily inserted therein and removed therefrom.

Further objects of the invention will appear from the following specification taken in connection with the drawings, which form a part of this application, and in which

Fig. 1 is a longitudinal sectional elevation of an extinguisher and support constructed in accordance with the invention;

Fig. 2 is a front elevation of the supporting bracket;

Fig. 3 is a rear elevation of the extinguisher casing;

Fig. 4 is a transverse sectional elevation taken substantially on line 4-4 of Fig. 1; and

Fig. 5 is a sectional elevation of the lower end of the extinguisher and casing showing a heat controlled releasing device for the breaking hammer.

The invention briefly described consists of a container, preferably formed of frangible

material, and containing a fire extinguishing liquid, such as carbon tetrachloride, and means for supporting the container in such a way that it can be easily and quickly removed from its support and manipulated to break the container and release the fire extinguishing liquid.

The frangible container is enclosed within in a casing having a body portion, a top portion and a bottom portion. A hammer or plunger is slidably mounted in the bottom portion and is adapted to be forced inwardly by a blow thereon to break the frangible container and liberate the liquid contained thereby. Means is also provided for supporting the frangible container in such a way that it will not be accidentally broken but will be held against displacement in the casing. The top portion of the casing is detachably connected to the body portion in such a manner that it can be readily removed, thus facilitating the replacement of the container after the extinguisher has been used.

Further details of the invention will appear from the following description.

In the particular form of the invention illustrated the extinguisher is supported on a bracket consisting of an elongated plate 10 having its lower end 11 extending laterally to a position beneath a hammer hereinafter described. The upper end of the plate is folded back to form a lip 12.

If desired, the bracket can be supported by the loop formed at the junction of the lip 12 and the main body portion of the bracket 10. For instance, the lip may be placed over the bottom edge of a pocket in the door of an automobile. In order, however, to facilitate the attachment of the bracket to a vertical wall, countersunk openings 14 and 15 are formed in the body portion of the bracket and in the lip 12. An opening 16 is also formed in the bracket in alignment with the countersunk opening 14 to permit the passage of a screw through the opening 14.

The fire extinguisher illustrated comprises an elongated tubular container 20 formed of frangible material, such as glass, and having a depression 21 at the lower end 10.

thereof. The glass or material at the depression 21 is preferably thinner than the remaining portion of the wall to make it more frangible.

- 5 In order to protect the frangible container from accidental breakage the container is housed in and covered by a casing comprising a central or body portion 25, a bottom 26 and a cap or cover 27 which forms the top 10 of the casing.

The body portion 25 consists of a cylindrical band or sleeve having outturned flanges 30 and 31 tapered longitudinally with respect to each other, as shown in Fig. 3. The 15 body portion has a plurality of lugs or lips 32 struck out from the material thereof and extending through the dome shaped bottom 26 of the casing. From the showing in Fig. 1 it will be noted that the lower peripheral 20 portions 35 of the container are so formed that they will rest on the portions 36 of the dome shaped bottom 26.

The cover or cap 27 which forms the top of the casing is provided with lugs 40 which are 25 adapted to engage recesses or openings 41 formed along the upper edge of the body portion 25 and the cap is also provided with a laterally extending lug 42 which extends through a slot 43 formed in the back portion 30 of the wall of the body portion 25. A spring 45 is positioned within the cap 27 and presses against the upper end of the container in order to prevent end wise movement of the container in the casing and to hold the container 35 against the bottom 26.

In order to facilitate breaking the frangible container a hammer having a head 48 and a shank 49 is slidably mounted in a bushing 50 carried by the bottom portion 26 of the 40 container. In the form of the invention shown in Figs. 1 to 3 inclusive the hammer is normally pressed by a spring 52 against the depressed portion 21 of the lower end of the container. The portion 11 of the bracket 45 extends beneath the lower end of the hammer shank 49 and prevents accidental engagement therewith.

The casing and container is secured to the bracket by means of resilient legs 60 and 61 50 of a U-shaped spring 62. The spring is secured to the front face of the bracket 10 by means of flanges 63 and lugs 65 and 66 formed on the flanges and extending into engagement with the spring. The upper ends 55 of the legs 60 and 61 can slide beneath the lugs 66 to permit the legs which are bowed inwardly to be forced outwardly. In order to mount the casing and container on the bracket the casing is positioned as shown in 60 Fig. 4 with the legs 60 and 61 engaging between the outer surface of the band or central portion 25 of the casing and the flanges 37 and 38 of the clamping plate 10. This can be accomplished by forcing one of the 65 legs laterally and snapping the other leg into

the position shown in Fig. 4 or by moving the container downwardly so that the tapered clamping plate will be positioned with its flanges behind the springs legs 60 and 61.

In order to use the device shown in Fig. 2 the container is removed from the bracket by sliding it upwardly or merely by grasping it firmly and pulling it away from the bracket and then the shank 49 of the hammer is engaged against any suitable object and forced inwardly, breaking the lower end of the frangible container. The bottom 27 of the casing has a plurality of perforations or openings 55 to permit the fire extinguishing fluid to pass therethrough.

In the form of the invention shown in Fig. 5 the hammer is normally held in retracted position spaced from the depressed portion 21 of the container by means of a pin 56 which extends through the hammer shank 49 and beneath the lower end of the bushing 50. The pin 56 is preferably formed of fusible metal so that in case of fire the pin will melt, thereby permitting the spring 52 to force the hammer upwardly into engagement with the container, causing the container to be broken and the fire extinguishing fluid to be released. The pin 56 may, if desired, have a cord 57 secured thereto and extending in a position in which it will be accessible so that the pin can be manually withdrawn, thus releasing the hammer.

As above stated, in order to use the extinguisher, it is merely necessary to grasp the casing and remove it from the bracket, whereupon the hammer can be forced inwardly to break the container and the fluid can be sprinkled or poured on the fire. Also, as stated, with the device shown in Fig. 5, in case of fire the pin 56 will melt, thus automatically releasing the fire extinguishing fluid.

In order to replace the container after the extinguisher has been used, pressure is exerted against the cap 27 above the lugs 40 to release the lugs from the depressions or openings 41 in the body portion 25. The cap is then swung about the lug 42 as a pivot, permitting the broken container to be removed through the top of the body portion 25 and a new container to be inserted in the casing. After a new container has been inserted the cover 27 is swung down again and the lugs 40 will snap into the depressions or openings 41, thus locking the cover in place.

It will be apparent from the foregoing specification that a simple and practical fire extinguisher and support have been designed and that the container is so supported and held that it will not be accidentally broken by jarring or chucking back and forth in the casing. Furthermore, the casing is so supported that it can be readily and quickly removed from the supporting bracket and the

extinguishing liquid can be released by tapping or striking a blow on the plunger.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, a casing comprising an elongated central portion, a perforated bottom and a removable top, a frangible container in the casing, a spring surrounding and engaging the top of the container and disposed between the container and top of the casing for holding the container against endwise movement in the casing, and a plunger 20 slidable in and extending through the perforated bottom of the casing for puncturing the container and releasing the fire extinguishing liquid therefrom.

2. In combination, a casing comprising an elongated central portion, a perforated bottom and a removable top, a frangible container in the casing, a spring surrounding and engaging the top of the container and disposed between the container and top of the casing for holding the container against endwise movement in the casing, and a plunger slidable in and extending through the perforated bottom of the casing for puncturing the container and releasing the fire extinguishing liquid therefrom, said container having an indented lower end and said plunger extending into the indented portion thereof.

40 In witness whereof, I have hereunto set my hand this 20th day of January, 1928.

WILHELM B. BRONANDER.
